UNITED STATES PATENT OFFICE.

ELLIOTT R. MOFFET, OF JOPLIN, MISSOURI.

OPEN-HEARTH LEAD-FURNACE.

SPECIFICATION forming part of Letters Patent No. 309,556, dated December 23, 1884.

Application filed May 14, 1884. (No model.)

To all whom it may concern:

Be it known that I, ELLIOTT R. MOFFET, of Joplin, Jasper county, and State of Missouri, have invented a new and useful Improvement in Open-Hearth Lead-Furnaces, of which the following is a full, true, and accurate description, reference being had to the accompanying drawings, which form a part of this specification.

10. The object of my invention is to increase the production and economize fuel in an open-hearth furnace, and at the same time to diminish the labor usually required in attending them. This I accomplish by making my 15 furnace double, in the manner hereinafter described, and by providing it with appliances for heating the air before it enters the tuyeres, while at the same time such air is made to keep the walls of the furnace sufficiently cool, 20 and the tuyeres are also kept from becoming too hot.

Reference being now had to the drawings, Figure 1 is a cross-sectional view of my double furnace on the line $x x$ of Fig. 2. Fig. 2 is a 25 plan view of the same on the section $y y$ of Fig. 1. Fig. 3 is a sectional view of the side of the furnace on the line $z z$ of Fig. 2, and Fig. 4 is a sectional view of the dividing-wall or back of the double furnace on the line $v v$ 30 of Fig. 1.

A A' and B B', which are the sole-plates and work-stones of the two furnaces, or rather of the double furnace, are all formed from a single iron casting, the construction and form 35 of which are clearly shown in the different views and sections of the drawings. This casting or platform is sustained at a convenient distance above the ground by any convenient supports, such as iron pillars C C, as shown 40 in the drawings.

The sole-plate of one side of my double furnace, as A', Figs. 1 and 2, is provided with a tube or covered passage-way, a , leading from the bottom of said sole-plate to a gutter, b , 45 placed to one side of the work-stone B'. As the melted metallic lead rises in the sole-plate A', it flows from the bottom of said plate into the gutter b , and thence into the ordinary casting-pot.

50 D, Figs. 1 and 4, is a cast-iron partition which divides the casting, forming the sole-

plates and work-stones into two parts or furnaces, and d, Figs. 1 and 4, is a tube or aperture formed in said casting, by which the melted lead in the sole-plate A is allowed to 55 flow into the sole-plate A', so that the product of both furnaces flows out through a single gutter, b .

E is a cast-iron box or trough, adapted to be placed upon the casting D, and to form part 60 of the same dividing-wall. It is kept full of flowing water, which enters at its bottom by means of the pipe e , and flows out at its top through the pipe e' . This water surrounds the tuyeres F, which may either form a part of 65 the box E or be placed in the same. The tuyeres F, as shown in Figs. 1, 2, and 3, are arranged in a line at the back of each furnace; and I prefer to use a large number, so that all parts of the furnace may be amply provided 70 with the air-blast. In furnaces of ordinary size, six, as shown in the drawings, I have found to give good results.

G is a cast-iron plate made to fit and cover the top of the box E, and it is provided with 75 holes g' , which register with the holes in the tuyeres F. The top of this plate is provided with three ridges, g^2 , which fit into corresponding depressions in the casting H.

H is a hollow cast-iron box provided with a 80 partition, h' , which divides it into two independent air conduits or flues, I and I'. It sets upon and is fitted to the lid G of the tuyere-box E, said lid serving as its bottom. The flues I and I' communicate, respectively, with 85 the flues formed in the side walls of the furnace by means of openings i and i' formed in the box H.

The partition or dividing wall made up, as above described, of the castings D, E, and H, 90 forms, as will be seen, the back of each of the furnaces.

J and J' are the side walls of the furnace, which are also made of cast-iron and are hollow. They are provided with openings marked 95 K and K', respectively, for the admission of air, and have partitions L cast or inserted in them. They have also openings j and j' , which register with the openings i and i' of the box H.

M is the chimney or stack, which is supported 100 upon the side walls, J J', in the manner shown in Figs. 1, 3, and 4.

In operation my furnace is charged in the usual manner. An air-blast is forced through the openings K and K' into the lower parts of the hollow side walls, J and J', and the blast is forced to each end of the side walls by means of the deflecting-plates L, after passing around the ends of which it passes through the upper parts of the side walls to the openings j and j', through which it enters the flues I and I', in which it is distributed to the tuyeres F. The air of course, before reaching the tuyeres, is highly heated by reason of its extended contact with the hot walls of the furnace, and these walls are at the same time kept below the temperature at which cast-iron is injured in the operation of these furnaces.

The even distribution of the hot blast through the multiple tuyeres enables my furnace to work the most refractory ores, and the operation is carried on at greatly-increased speed and relative diminution of fuel. Labor is also saved by reason of the fact that, as constructed by me, both furnaces deliver their metal through a single gutter.

It will be obvious to one skilled in the art that my furnace can be used for roasting refractory lead and silver ores as well as for smelting them, and I have found it to give excellent results when so used.

I have described my improvements as applied to a double furnace; but, as will be readily seen, the hollow iron walls with their deflecting-plates and distributing-apertures and the water-box for the multiple tuyeres can as readily be applied to a single as to a double furnace.

Having now described my invention, what I claim as new, and desire to secure by Letters Patent, is—

1. A double lead-smelting furnace consisting of an iron platform constituting the sole-plates and work-stones of both furnaces, having a passage, a b, on one side for the escape of the lead, and provided with a partition-wall having the opening d, substantially as shown and described.

2. A lead-smelting furnace having its sides made of hollow iron castings provided with deflecting-plates L, and its back made of a hollow iron casting opening into the hollow side walls, and provided with apertures for distributing air to the tuyeres, substantially as shown and described.

3. A lead-smelting furnace having its sides made of hollow iron castings provided with

deflecting-plates L, and its back made of a hollow iron casting opening into the hollow side walls, and provided with apertures for distributing air to the tuyeres, and having said tuyeres arranged in a line in the back of the furnace, so as to distribute the blast evenly in all parts of the same, substantially as shown and described.

4. A lead-smelting furnace having its sides made of hollow iron castings provided with deflecting-plates L, and its back made of a hollow iron casting opening into the hollow side walls, and provided with apertures for distributing air to the tuyeres, and having said tuyeres contained in a cast-iron water-box, forming a part of the back of the furnace, substantially as shown and described.

5. A furnace for lead-smelting, in which the air used for the blast cools the hollow sides and back of the furnace and at the same time becomes itself hot and is forced into the furnace through tuyeres placed in a portion of the hollow back of the furnace and cooled by a running stream of water, substantially as shown and described.

6. A double lead-smelting furnace having its side walls made of hollow cast-iron, provided with deflecting-plates L, and its back made up in part of a hollow casting provided with the flues I I', adapted to register with openings in the hollow side walls, in combination with multiple tuyeres opening into said flues, substantially as shown and described.

7. A double lead-smelting furnace having its side walls made of hollow cast-iron, provided with deflecting-plates L, and its back made up in part of a hollow casting provided with the flues I I', adapted to register with openings in the hollow side walls, in combination with multiple tuyeres situated in a water-box forming part of the back of the furnaces, substantially as shown and described.

8. In a double lead-smelting furnace substantially as described, a cast-iron back consisting of a casting, D, having a perforation, d, in combination with a cast-iron tuyere-box, E, having water-pipes e and e', and a cast-iron flue-box, H, having openings to admit the blast of air and to distribute the same to the tuyeres.

In witness whereof I have hereunto set my hand.

ELLIOTT R. MOFFET.
